UNITED STATES PATENT OFFICE.

ALBERT T. NEWMAN, OF KANSAS CITY, MISSOURI, ASSIGNOR TO NEWMAN OIL BURNER COMPANY, OF KANSAS CITY, MISSOURI, A CORPORATION OF MISSOURI

OIL BURNER.

Application filed February 19, 1923. Serial No. 619,889.

To all whom it may concern:

Be it known that I, ALBERT T. NEWMAN, a citizen of the United States, residing at Kansas City, in the county of Jackson and

5 State of Missouri, have invented certain new and useful Improvements in Oil Burners; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to oil burners and the primary object is to provide a simple burner which will efficiently vaporize hydro-carbon oils to convert them into gases to be mixed with air preparatory to ignition.

20 In order to provide an efficient burner, the oil should be thoroughly vaporized before it comes into contact with the air and the air should be combined therewith in such quantities as to promote combustion 25 thereof to the best advantage.

Hydrocarbon burner designers and manufacturers have long sought for a construction of burner wherein the accumulation of carbon will be reduced to a minimum be- 30 cause the accumulation of carbon in the burner passages obviously renders the same inefficient and in most cases, entirely inoperative.

I believe I have provided a burner where 35 the disadvantageous accumulation of deposition of the carbon will be practically nil but I have so constructed the burner that even should pure low grade oils be employed with a superabundance of carbon in them so as to cause some deposition of carbon, access can be readily had to the working passages so that the objectionable matter can be easily removed.

The novel construction of my invention 45 will be apparent by reference to the following description in connection with the accompanying drawings, in which

50 Fig. 1 is a vertical, longitudinal, sectional view through a burner constructed in accordance with my invention, and

55 Fig. 2 is a disassociated view of the several parts of the burner, the cap piece being shown in section.

Referring now to the drawings by numer- 55 als of reference:

1 designates a base having a downwardly projecting peripheral flange 2 whereby the main body portion of the base is supported above its support. The base is provided with a central opening 3 surrounded by an 60 upturned, curved flange 4 so that air can be directed through the opening and to permit the introduction of an oil supply pipe 5 therethrough. The oil supply pipe can be connected to any suitable source of supply, the port area of the pipe to be controlled by a valve 6. The discharge end of the pipe 5 is connected to a truncated cone 7.

The cone is inverted and it has a central 70 concaved portion 8 surrounding the discharge end of the pipe 5. A circumferential groove 9 surrounds the cup 8 and the edge of the groove 9 terminates at the outer wall of the cone. By reference to the drawings 75 it will be seen that the cone is hollow and that at its lower edge it is provided with a shoulder 10 and an outwardly extending flange 11. The shoulder has a groove 12 in it immediately below a circumferential 80 series of openings 13 in the wall of the cone.

The inner face of the cone-shaped wall of the cone is provided with brackets 14, having shoulders 15 which engage the upper edge 16 of a ring 17 supported by a priming 85 pan 18 having an overflow pipe 19. Therefore, the cone is supported both by the pipe 5 and by the ring 17, the main support, however, being the ring 17 on the priming pan.

The brackets 14 are of sufficient widths 90 to space the inner wall of the cone away from the ring 17 so as to provide a mixing chamber or space 20 between the ring and the cone, it being apparent by reference to the drawings that the diameter of the cone 95 is considerably greater than that of the ring.

Supported by the cone is a cap piece or member 21. This is also conical and it has a shoulder 22 which rests upon the flange 11. The top 23 of the cap is curved on its interior face to conform to the curvature of the top of the cone 7 so that a tortuous passage is provided for the passage of the hydrocarbon oils discharged from the pipe 100 5. Therefore, the oils follow a tortuous passage to the overflow edge of the cone 7 and then pass through the chamber or space 105 24 between the inner face of the cap and the outer face of the cone. The space 24 is 110

formed by spacing the inner wall of the cap away from the outer wall of the cone as it fits over the shoulder 10. The cap is also provided with radial wings 25, extending from the outside wall so as to radiate the heat from the burner.

When the parts are assembled and oil is permitted to pass through the pipe 5, it will overflow into the cup 8, from there into the 10 groove 9, over the side of the cone 7, through the openings 13 and into the priming pan. If the flame is extinguished while the oil is flowing, the oil may escape through the overflow pipe 19.

15 The oil in the priming pan can be ignited so that the burner will become hot. When it does, the oil issuing from the pipe 5 will be generated into vapor or gas. It will flow over the top of the truncated cone 7 through 20 the space 24 and through the holes 13. The air passing through the opening 3 and through the ring 17 will pass over the upper edge 16 of the ring and combine with the gas in the mixing space or chamber 20. Then it 25 will pass downwardly and upwardly, guided by the downwardly and upwardly curved peripheral flange of the priming pan so that the flame will be directed outwardly and upwardly in the form of a ring. It not only 30 will provide the necessary heat but it will also maintain the burner hot so that after the burner has been primed, the burning vapors will maintain the burner at sufficient temperature to vaporize the oil.

35 It is an important feature of my invention that the holes 13 are provided in the wall of the truncated cone so that they combine the maximum amount of air and provide a highly combustible mixture just before it 40 reaches the point of combustion. Such a construction will make a burner which will consume practically all of the hydrocarbon oils without residue and, therefore, there is little liability of accumulation of carbon. 45 If there should be any accumulation, however, the cap can be readily removed and the carbon disposed of.

What I claim and desire to secure by Letters-Patent is:

50 1. An oil burner comprising a pan having a central collar or ring, a hollow truncated cone having an inclined wall on the inner face of which are brackets resting upon the top edge of the ring, the inclined wall having 55 circumferential series of openings above the lower edge thereof, a cap surrounding the top and inclined wall of the cone and

spaced therefrom, the lower edge of the cap extending below the opening and means for introducing oil through the top wall of the 60 cone into the space between the cone and the cap, the cone being spaced from the ring which supports it.

2. An oil burner comprising a pan having a circumferential trough, an inverted cone 65 having a recess in its top, the cone being smaller in diameter than the pan and supported above the edge of a central opening in the pan, the cone having a depending wall with transverse openings therein, the wall 70 of the cone being spaced from the pan, a pipe for feeding oil into the center of the recess in the top of the cone so that the oil may flow over the depending vertical wall of the cone and a cap covering the cone and having a depending wall extending to the bottom edge of the wall of the cone.

3. An oil burner comprising a pan having a circumferential trough, a cone smaller in diameter than the pan and having a circumferential depending wall surrounding a central opening in the pan and spaced therefrom, the cone having transverse openings 80 in its vertical wall above the bottom edge thereof, a pipe for feeding oil over the top 85 of the cone and a cap enclosing the top and vertical wall of the cone but in spaced relation to the cone.

4. An oil burner comprising a pair of inverted cones, one fitting over the other and spaced therefrom, both cones having a circumferential depending relatively thin wall, the inner cone having transverse openings between the top and bottom edge of the wall, brackets on the inner wall of the inner cone and a ring upon the edge of which the brackets rest.

5. An oil burner comprising a pan having a central opening, an inverted cone supported by the pan but spaced therefrom, the cone having a relatively thin depending wall surrounding a central opening in the pan and provided with rows of transverse air openings, a grooved portion at the lower part of the depending wall, an outer cone 100 spaced from the inner cone and having an inner wall conforming substantially to the wall of the inner cone, the inner cone having means for supporting the outer cone and means for supplying oil to the top of the 105 inner cone.

In testimony whereof I affix my signature.

ALBERT T. NEWMAN.
